UNITED STATES PATENT OFFICE.

JOHN C. SHAMBOW, OF WOONSOCKET, RHODE ISLAND.

TENSION DEVICE FOR SHUTTLES.

1,230,525.

Specification of Letters Patent. Patented June 19, 1917.

Application filed July 17, 1916. Serial No. 109,706.

To all whom it may concern:

Be it known that I, JOHN C. SHAMBOW, a citizen of the United States, residing at Woonsocket, in the county of Providence and State of Rhode Island, have invented new and useful Improvements in Tension Devices for Shuttles, of which the following is a specification.

My present invention pertains to tension devices for loom shuttles, and contemplates the provision of a simple, durable and reliable device for subjecting the filling to such tension that it is effectually prevented from "ballooning"—i. e., too freely leaving or flying out of the shuttle.

To the attainment of the foregoing the invention consists in the peculiar and advantageous tension device as hereinafter described and claimed.

20 In the accompanying drawings which are hereby made a part hereof:

Figure 1 is a plan view of so much of a shuttle as is necessary to show the application of my novel tension device.

25 Fig. 2 is a side elevation of the same.

Fig. 3 is an elevation showing that side of the device adjacent to the spindle of the shuttle.

Fig. 4 is a view on line 4—4 of Fig. 6.

30 Fig. 5 is a perspective of the yarn-engaging plate.

Fig. 6 is a transverse section showing, the improved device as properly positioned in a shuttle body.

35 Similar numerals of reference designate corresponding parts in all of the views of the drawings.

The shuttle body 1 is provided with the usual channels 2 and 3 for the passage of filling 4, and my novel tension device 5 is arranged in the body at a point between the channels 2 and 3, as clearly appears in Figs. 1, 2 and 6.

40 The tension device comprises a casing 6, a metallic plate 7 positioned in the casing and having an upright portion designed to rest at one side of the filling as the latter passes outwardly in the shuttle, and a spring-pressed shoe 8, also arranged in the casing and designed to yieldingly bear against the passing filling. As clearly shown in Fig. 4, the casing 6 is preferably formed of a strip of sheet-metal bent into rectangular form and with its ends arranged adjacent to each other as indicated by 9. The ends of the casing are open (Figs. 4 and 6) and in the

forward side of the casing—i. e., the side remote from the spindle in the shuttle, is a slot 10, Fig. 6, which extends downwardly from the upper end of the casing as shown. 60 It will also be noticed by reference to Fig. 3 that in the opposite side of the casing an opening 11 is formed for the passage of filling; the said opening 11 being located below the upper end of casing 6, and being surrounded by a finger 12 and connected with a curvilinear channel 13 which extends around the finger 12 to the upper end of the casing. The finger 12 serves the important purpose of holding the filling down in the 65 openings 10 and 11. The metallic plate 7 comprises an upright portion for coöperation with the shoe 8, and upper and lower arms that terminate in lips and are designed to maintain the upright portion in proper 70 working position. The said plate 7 is further retained in position by a screw 15 which is mounted in the shuttle body and bears against its lower lip as illustrated in Fig. 6. 80

As illustrated in Fig. 6, the shoe 8, which is preferably of porcelain, is rounded at the upper end of its side adjacent to the upright portion of the plate 7 to facilitate the placing of the filling, and is backed by a spring 85 16 which, in turn, is backed by a screw 17 mounted in the shuttle body; the said screw serving for the regulation of the spring when the same is necessary.

It will be gathered from the foregoing 90 that my novel device is simple and inexpensive in construction, and is susceptible of being expeditiously and easily placed and secured in shuttles of the usual construction; also, that the device is capable 95 of subjecting the filling to the tension necessary to prevent "ballooning," and this without interfering with the proper passage of the filling from the shuttle.

Having described my invention, what I 100 claim and desire to secure by Letters-Patent, is:

1. The combination of a shuttle body having spaced channels for the passage of filling and also having a recess intermediate 105 said channels, a tension device positioned in said recess and comprising a casing open at its ends and having openings in its side walls for the passage of filling and also having a retaining finger above one of said 110 openings, a plate arranged in said casing and having an upright portion and arms

reaching from the upper and lower ends of said portion and terminating in lips that bear against walls of the recess, and a spring-backed shoe movable in the casing and on the lower arm of the plate and opposed to the upright portion of the plate, a screw mounted in the shuttle body and opposed to the spring, and a screw also mounted in the shuttle body and bearing against the lower lip of the plate.

2. A tension device for loom shuttles, comprising a casing open at its ends and having means in its side walls for the passage of filling, a plate arranged in said casing and

having an intermediate upright portion and 15 arms that reach in opposite directions from the upper and lower ends of said portion and terminate in lips, and a spring-backed shoe movable in the casing and on the lower arm of the plate and opposed to the upright 20 portion of the plate.

In testimony whereof I have hereunto set my hand in presence of two subscribing witnesses.

JOHN C. SHAMBOW.
